8 Sheets-Sheet 8

This technical drawing illustrates a complex mechanical assembly, likely a component of a larger machine. The drawing is labeled with numerous reference numerals, including:

- Fig. 39: A vertical assembly on the left, featuring a base labeled 30, a central vertical structure labeled 80, and a top section labeled 81. A horizontal pipe labeled 250 connects to a vertical pipe labeled 82, which is further connected to a horizontal pipe labeled 46.
- Fig. 38: A horizontal assembly on the right, showing a large rectangular frame. Key components include a vertical pipe labeled 99, a horizontal pipe labeled 4, a vertical pipe labeled 97, a vertical pipe labeled 96, a vertical pipe labeled 95, a vertical pipe labeled 13, a vertical pipe labeled 46, a vertical pipe labeled 30, a vertical pipe labeled 28, a vertical pipe labeled 29, a vertical pipe labeled 261, a vertical pipe labeled 262, a vertical pipe labeled 263, a vertical pipe labeled 83, a vertical pipe labeled 82, a vertical pipe labeled 253, a vertical pipe labeled 255, a vertical pipe labeled 254, a vertical pipe labeled 49, a vertical pipe labeled 252, a vertical pipe labeled 48, and a vertical pipe labeled 4.

CONSTRUCTION OF LOCOMOTIVE BOILERS,
ETC.

Edmund H. Blunt, Brooklyn, N. Y.

Application April 13, 1931, Serial No. 529,726

7 Claims. (Cl. 110—57)

One object of my invention is the reliable supplying of sufficient amounts of highly heated air to the boiler to properly promote combustion therein.

5 Another object of my invention is to provide adequate and effective means for the use of powdered or finely crushed fuel in a locomotive fire box.

In one arrangement of my invention the air 10 enters a duct adjacent the smoke stack and passes first through a chamber where it is moderately heated by waste steam. From this first heater, the air is drawn into a second chamber where it is heated by hot gases from the fire box. The highly heated air then passes into the fire box. Part of the hot air may be used to carry 15 the fuel along with it into the fire box.

In applying this arrangement to a modern 20 type locomotive a number of improvements have been developed, i. e. e.

1. Details of means for the practical supply of pre-heated air to the boiler furnace.

2. Adjustable means to pass such pre-heated air through the boiler independently of the main engine exhaust.

25 3. Means employing pressure developed by the moving engine to force incoming air through the heater.

4. A fan or blower drawing air from the first 30 stage air heater and forcing said heated air through the second stage heater, and to the boiler.

5. Details of a first stage air heater using surplus steam to warm the contained air.

35 6. Details of a second stage air heater using hot fire box gases to heat the contained air.

7. A thimble through the inner and outer walls of the boiler "water-legs" to permit the passage of certain amounts of fire box gases to without the 40 furnace or fire box limits.

8. A secondary smoke stack into which the required fire box gases may pass.

9. A damper in the passage to the secondary 45 stack that automatically tends to close whenever the escaping gas temperature rises above a determined point, and vice versa.

10. A maximum sized combustion chamber to promote the complete burning of fuel.

50 11. A three pass, reverse flow, furnace whose main passes are substantially horizontal and parallel.

12. A combustion chamber wherein fuel is admitted to the upper pass and successively progresses downward.

13. A combustion chamber with walls protected by water-screen tubing of a flattened or oval type.

14. A hot air passage to the pulverized coal supply to assist its delivery to the boiler.

15. A transparent hinged "wing" to widen the "bell mouth" opening into the first heater.

16. An emergency oil burner near the coal burner that will maintain a small fire and so reduce "standby" losses of fuel.

These features and others singly and in combination, constitute marked improvements in the construction of the modern locomotive, all tending to increase its economy and effectiveness.

Whereas the pre-heating of the air of combustion by the waste heat of the escaping gases 15 through the stack is a recognized economy in stationary plant practice, the space restrictions on a locomotive would seem to prevent its practical application on the latter, especially were the general form and dimensions kept the same. 20

In fact, the prevailing forms of plates and heating surfaces as used by the former are proportionately so great that it is impossible to find spare room within the locomotive clearance limits. Also the distance from the source of heat, 25 the smoke stack to the fire box in the rear adds to the difficulty of providing a conduit of sufficient cross sectional area to carry the heated air along the whole length of the boiler body and to its delivery to the fire box. 30

I propose overcoming this difficulty by using some of the waste heat of the escaping steam instead, conveying the latter by means of a pipe leading from any exhaust steam passage to an air pre-heater to be described. The problem 35 therefore requires the providing of a suitable pre-heater, a place to install it and means for expeditiously conveying the resulting heated air through the fire box of the locomotive.

The locomotive exhaust steam under normal 40 back pressure from the engine might approximate a temperature of 225 degrees Fahr. As the heat transference through metal surfaces is proportional to the difference in temperature between this steam and the air to be heated, it is obvious 45 that the resulting air temperature will be less than that of the steam depending on the amount of air to be heated.

Owing to the great amount of air required and the limited space in which to install this first 50 stage heater, the temperature may not be high enough for a proper combustion, so I propose taking this partly heated air and passing it through a second stage heater, thereby supplying extremely hot air to the boiler fire box or furnace. 55

This second heater is to be warmed by a variable amount of hot gases withdrawn from the fire box and used to further heat this air.

Means to regulate the flow of this gas and its temperature will be described. An induced-draft fan may be introduced into the smoke box end of the boiler to draw the products of combustion through the fire tubes. I prefer, however, to use a forced draft system with a closed fire box, giving a more perfect control of the varying percentages of air needed by the burning coal.

By introducing a fan or blower after the first stage heater and before the second stage heater, a further improvement is accomplished, as the first heater has the incoming cool air drawn through it delivering this moderately heated air to the fan which is thereby not overheated. This hot air is then forced into the second heater which is constructed so that it is not affected mechanically by the previously heated air or by its overheat.

This arrangement not only keeps the fan at a reasonable temperature and in excellent operating condition, but permits its installation alongside of the boiler, accessible but sheltered. Contrariwise, it would be difficult to properly mount a fan that would first force the cold air into the first heater and then into the second one, should my above mentioned system of "Indu-force" or "induced-forced draft" be omitted.

On the drawings, Sheet 1, is shown a simple air-heater assembly as established on an existing type of a large sized modern American locomotive, increasingly coming into use. This suggested adaptation of my air-heater is comparatively inexpensive and involves no appreciable change in the construction of the locomotive, being readily applied to those already built. The heated air may be applied to any type of furnace to promote efficient combustion, but preferably to one with a closed fire box.

On Sheet 2 is shown the same type of locomotive but with the smoke box, or front end extended forward to allow greater room for a "saddle-type" of air heater mounted directly behind the smoke stack. To provide for a maximum capacity fire box that will more efficiently burn fluid or "flowing" fuel, such as powdered or pulverized coal or oil, I prefer transferring the auxiliary tractor or booster from the rear trailing axle to the tender axle thus permitting an appreciable lowering of the fire box and ash-pan as shown. This change only calls for a new water-leg fire box supported on a new type trailing truck, the general proportions of the locomotive remaining unaltered. This may be readily seen on Sheet 6.

To provide for the greatest length of travel for the fuel and also to keep it in suspension the longest time before reaching the fire tubes I have designed a three-pass fire box as shown on Sheet 6.

Owing to the intense heat generated in the third or "bottom" pass and the necessity of absorbing enough of it to reduce the temperature and so prevent the fusing of the enclosing fire-brick I have devised a pipe "water-screen" of parallel "flat" or oval sections that may lie closely together and also properly fastened into common supply headers. These are in detachable sections or units and are freely interconnected to take care of the large expansions due to temperature changes that may occur.

Another important feature is the use of a "secondary smoke stack", preferably located at or near the rear of the boiler, as shown. This and

an automatically controlled damper will be duly described. Advantage is also taken of the rapid forward motion of the locomotive to assist in driving the cool air into the forward end of the first stage heater by means of a bell-mouthed opening and an outswinging "shutter" that will not appreciably interfere with the forward vision of the engine crew.

In some instances it may be advantageous to heat the first stage air heater to a moderate temperature by the use of smoke stack gases, and then deliver the air to the second stage heater, but the steam heated means is the preferred way.

In the description of my present invention the following figures are shown:

Fig. 1 is a left side elevation of a standard type locomotive with my invention applied.

Fig. 2 is a front elevation on the line 2-2 of Fig. 1.

Fig. 3 is a section on the line 3-3 of Fig. 1 showing the bell mouth and shutter.

Fig. 4 is a side elevation of Fig. 3 showing the bell mouth of the heater and the attached shutter.

Fig. 5 is a top view of the bell mouth on the line 5-5 of Fig. 3.

Fig. 6 is a section of the fire box water-leg on the line 6-6 of Fig. 1.

Fig. 7 is a side elevation of a modification of the construction shown in Fig. 1.

Fig. 8 is a top plan of Fig. 7 with the roof of cab removed, arrows showing the flow of heated air to the fire box, etc.

Fig. 9 is an enlarged side elevation of the forward half of the locomotive of Fig. 7.

Fig. 10 is a half top plan of Fig. 9 with parts 35 of the air heater broken away to show interior.

Fig. 11 is a front elevation of the construction of Fig. 9 comparing the first stage heater casing with the cab outline.

Fig. 12 is a part section on the line 12-12 of Fig. 9.

Fig. 13 is a part section on the line 13-13 of Fig. 9 showing the turbine-blower and air inlet.

Fig. 14 is a part section on the line 14-14 of Fig. 9 with transition piece to the second stage heater.

Fig. 15 is a part section through the rear portion of the first stage heater on the line 15-15 of Fig. 10.

Fig. 16 is a part section through the front portion of the same heater on the line 16-16 of Fig. 10, showing groupings of 3-plate heating units.

Fig. 17 is a side view of the nesting headers for curved heating tubes, on line 17-17 of Fig. 15.

Fig. 18 is an enlarged detail of the header nesting of Fig. 15.

Fig. 19 is a section on line 19-19 of Fig. 18 showing groups of fins mounted on the curved heating tubes.

Fig. 20 is an enlarged plan of a five-plate type of heating unit that may be used in Fig. 16.

Fig. 21 is an enlarged side elevation of the rear part of the locomotive of Fig. 7 and is a continuation of Fig. 9 and shows the assembly of the second stage heater.

Fig. 22 is a part top plan of Fig. 21 with the cab omitted, also showing the coal and air piping to the tender.

Fig. 23 is a left-half section of the boiler rear end on the line 23-23 of Fig. 21.

Fig. 24 is a vertical section through the center of the boiler fire box on the line 24-24 of Fig. 22 showing the coal burner, three-pass furnace and supports, etc.

Fig. 25 is a left-half section of the boiler on the line 25—25 of Fig. 24.

Fig. 26 is a right-half section of the boiler on the line 26—26 of Fig. 24.

Fig. 27 is a right-half plan of the ash-pan and truck frame on the line 27—27 of Fig. 24.

Fig. 28 is a portion of a plan on the line 28—28 of Fig. 24 showing the burner and air-supply.

Fig. 29 is a vertical mid section of the boiler 10 similar to Fig. 24 and showing water-screen piping to protect parts of the ash pan.

Fig. 30 is a plan of the piping on the line 30—30 of Fig. 29.

Fig. 31 is a left-half section on the line 31—31 15 of Fig. 29.

Fig. 32 is a right-half section on line 32—32 of Fig. 29.

Fig. 33 is a detail plan showing means of attaching "flattened" water-tubes to their headers.

Fig. 34 is a sectional view and side elevation of the parts shown in Fig. 33.

Fig. 35 is a front elevation of the pipes and adjacent headers on the line 35—35 of Fig. 33.

Fig. 36 is an elevation and section on the line 25 36—36 of Fig. 35 showing inside bolt connection.

Fig. 37 is a sectional plan through water piping connections to an outside water header shown on line 37—37 on Fig. 29.

Fig. 38 is a sectional elevation of the second-30 stage air heater but in two divisions controlled by several air dampers to give a varied control of the heated air.

Fig. 39 is a side elevation of a second stage air 35 pre-heater showing an additional hot gas discharge regulation.

1 is the locomotive boiler shell, 2 is an existing type of smoke stack, 3 is a proposed type of a "primary" smoke stack, 4 a "secondary" smoke stack, 5 the running board, 6 the main steam cylinder, 7 the driving wheels, 8 a typical 4-wheeled trailing truck, 9 a proposed 4-wheel trailing truck, 10 the rear tube sheet, 11 the fire box crown sheet, 12 the side water legs of the fire box, 13 the rear water leg or back end of the 45 boiler, 14 the combustion chamber, 15 location of prevailing type of fire grate with attached ash pan, 16 the cab, 17 the cab floor, 18 a front window of the cab, 19 the engine-frame, and 20 and 21 the front and rear trailing axles, respectively, 50 of said trailing trucks.

The mud ring is 22, while 23 is the coupling, 24 the tender and 25 a proposed ash-pan casing.

It appears preferable to install the air-heating apparatus in duplicate, for instance, on both sides 55 of the boiler center line which I have marked C/L, this symbol also denoting other center lines about which other parts may be symmetrical. Generally speaking, the same reference number applies to both sides of the locomotive.

60 It will be noted, however that occasionally and where part-sections occur, that a right side apparatus may appear along with a left side companion installation.

On these occasions I may add a letter "R" to 65 the number to signify the right hand member, or an "L" to mean on the left hand. Thus 12L is the "left" hand water leg while 12R is the corresponding "right" hand water leg.

In Fig. 1 the incoming cold air enters the forward 70 end of the first stage heater 26, which in Fig. 7 is divided into a forward portion, 26A and a rear portion 26B. It is there partly heated by steam means and passes out and downward through air duct 27 to a fan or blower 28, prefer- 75 ably of the steam-turbine driven type, and here

shown installed below the running board 5. Fan 28 is operated by the throttle controlled live steam conduit 27a.

In Fig. 1, fan 28 delivers the air to a circular duct 29, and through a transition piece 30, and to 5 a rectangular casing 31 that is an enclosure for the secondary heating operation and known as the second stage heater. In Fig. 6 hot gas from the combustion chamber 14 passes out through the water leg thimble 33, hot air conduit 34 to 10 the hollow heating conduits 35 within the heater casing 31, still further warming the air delivered to this heater by fan 28. A certain amount of hot gas-flow within the conduits 35 is necessary 15 to promote an exchange of heat.

This may be accomplished by discharging the cooled gases through an external control valve or damper 36, to the atmosphere or otherwise.

The air of combustion heated to its highest temperature passes through the heater end 37 20 into conduit 38 to the fire box or where ever else required. Its use in this manner is an economy when ever applied to any type of furnace or used with any kind of fuel.

To avoid unnecessary duplication, the front end 25 of heater 26 is shown with its bell-mouth features omitted in Figs. 1, 2, 7, 9, and 10. On Figs. 3, 4, 5, and 8 the bell-mouth 40 is shown, also a transparent shutter or wing 41 hinged to it. This shutter is normally kept open, as shown, 30 by a spring 42 forcing the shutter against an adjustable stop 43 that regulates the outward spread of said shutter. Passage along the running board 5 may be made by pushing shutter 41 to the dotted position 44 of Fig. 5.

Fig. 3 also shows a dotted outline of the cab 16 and the outlook window 18. The shutter 41 is designed to permit a view of the track through this window and also to allow a proper view of 40 any overhead signals that the train may be approaching.

Fig. 7 has been separated on a line through the fourth driving wheel marked 45, into a larger scale forward portion as shown on Fig. 9 and a rearward portion as shown on Fig. 21.

Fig. 10 shows the two different air-heating systems that may be installed on top of the boiler. Attention is here drawn to a heater design providing the greatest capacity steam air-heater on top of the boiler barrel while at the same time 50 allowing forward vision from the cab windows such as is shown in the front end view of Fig. 11.

There are at present two different systems of air heating, and certain operating conditions seem to govern the choice of which may be the 55 preferable. One system depends on smooth, hollow plates to transmit the heat, while the other system consists of small-diameter parallel tubing on which are assembled closely placed plates, very thin, and whose planes are at right angles to the 60 axis of each tube. Believing that the use of both these systems is valuable in operating my first stage heater I have assembled the "smooth-plate" system in the forward portion, 26A, while using the "fin-tube" principle in the rear section, 26B of said heater.

A partial cross section of the plate-system is shown in Fig. 16 and the fin-tube in Fig. 15, both to be described later.

A turbo-driven fan such as shown at 28 may 70 be mounted on one side of the locomotive only, though it appears preferable to employ two smaller fans or blowers, one on each side to give flexibility to the varied power demands.

In Figs. 7 and 21, 46 is a second-stage air 75

heater of different internal construction from heater 31 of Fig. 1. Air from transition piece 30, but partially heated, is forced through it, becoming highly heated by later described means 5 and driven through the rear portion 47 and into transverse duct 48 that may connect with a similar duct 47R connecting with a similar heater on the right side of the locomotive.

An air outlet 49 from duct 48 is joined by a 10 flexible or articulated conduit 50 to pipes 51R and 51L, the latter being connected to the left fuel handling system 52L.

Prepared fuel from the tender 24 may enter 15 52L and be conveyed forward by the worm 53 into an air-lock such as 54. This air lock may use revolving paddles 55 that admit coal to a lower chamber (not shown) into which 51L is also forcing heated air. This air lock is designed to prevent the air from backing up into 52L. 20 A chain or belt 56 may be used to keep the paddles 55 in step with the worm 53.

Coal is forced by the heated air (or by other suitable means) into duct 57, flexible pipe 58, connecting pipe 59 and pipe 60 that enters the 25 backhead 13 of the boiler. A swivel or universal joint 61 permits adjustment of the fuel discharge to different portions of the firing chamber or pass 10. A sufficiently large thimble through 13, such as 62 (similar to 64 of Fig. 24) permits this.

30 To pipe 60 is attached an accepted type of coal-burner such as 65 (see Fig. 24), that can be moved or rotated by said pipe. Several of these burners may be installed and the amount of fuel consumed may be regulated by changing the 35 speed of the worms 53, by damper adjustment (not shown) by change of fan speed and amount of air supplied, singly or in combination. The burner 65 distributes the incoming coal, well diffused and mixed with the proper amount of hot 40 air, and ready to ignite in the shortest interval of time.

The fuel and air enter the upper pass 70 and are deflected by the baffle wall 71 into the second pass 72. Then backward, downward and forward 45 40 through the third pass 73, assisted by the baffles 74 and 75, all shown in Fig. 24.

The hot gases then pass to the rear tube-sheet 10, through the flues and fire tubes 76, heating the water within the boiler, and thence out the 50 smoke stack 3 to the atmosphere.

Heat is supplied to the second stage heater 46 by hot fire box gases that may pass through the water legs 12, by means of thimble openings 79, into connecting conduits 80, and to hollow heating elements 81 contained within the heater casing 46.

The gas contents of 81 are discharged into an external conduit 82 leading to the secondary smoke stack 4 and thence to the air.

60 Somewhere within the conduit 82 is preferably placed a damper or draft regulator 83 to control the final passage of the gas escaping to the atmosphere. This damper is preferably automatic, the type shown being actuated by a thermostatic control. This control includes a thermo-couple 84 having wiring 85, which may be inserted into the gas stream, and the variations of heat within the passage 82 will electrically affect a control box such as 86 connected to a primary or storage battery 87 and a solenoid 88.

The control 86 is adjusted to function whenever the heat impinging on 84 rises above a pre-determined temperature. Box 86 allows a current to pass from 81 to 88 to operate valve 89, ad-

mitting steam or air to cylinder 90. Also the solenoid may directly operate damper 83.

Piston 91 within a cylinder 90 will cause damper 83 to rotate thereby controlling the hot gas discharge into stack 4.

To make this discharge more effective I propose introducing a steam jet 92 into the secondary stack 4, as an additional draft control. A valve 93 is in the pipe line 94 leading from some steam supply, such as the steam discharge of the fan-turbine 28.

The force of this jet should increase as the air flow through the heater becomes greater, as a greater amount of heat has to be transmitted to this air, and necessitates a greater flow of hot 15 gases through the heating elements and out through the secondary stack to the atmosphere.

As this air flow is proportional to the steam that drives the turbine, the increase of exhaust steam discharged to the jet tends to stimulate the 20 hot gas flow just when it is most needed.

The heated air within heater 46 has already been described as passing to the tender and ultimately to the coal burner 65.

I may divert varying amounts of this air from 25 the heater such as from another outlet 95 and into a conduit 96, to and above the top, and towards the center of the boiler, then entering the cab, passing down through conduit 97 (Figs. 23, 24, 28) through thimble 64, into duct 98, within 30 upper pass 70, and to burner 65 in a well-known manner. Various dampers such as 99 may be employed to regulate the amounts of air supplied in this manner.

Duct 98 may connect with a fire brick passage 35 such as 100 controlled by valve 101 discharging through various openings such as 102, so as to conduct additional air to different parts of the firebox as may be required to maintain the most perfect combustion.

40 Ignition-boiler pass 70, reverse-pass 72, and ash-pan pass 73 are separated by firebrick arches 103 and 104 carried on arch tubes 105 and 106 respectively. Firebrick wall 107 is used to separate the igniting gases from the cooler metal walls 45 of the boiler, and to maintain an incandescence at other times to reheat the fuel when again starting up the burners.

Water enters arch tube 105 from the rear head 13 and discharges forward into the boiler as 50 shown. I may provide a more flexible connection such as shown in the lower level, wherein water from a vertical riser 108 supplies a header 109 carried at one end by riser 108 while the other end is supported in a pocket 110 recessed into 55 the water-leg 12 as shown in Fig. 32. The lower arch tubes 106 are supplied by header 109.

Arch tubes 105 and 106 convey the water forward to the boiler, having sufficient flexibility to take care of excessive temperature variations. 60 These tubes are spaced apart to clear each other at passing points. A wider spacing of these tubes occurs at the center to allow room for entrance and repairs, this space being covered by the arched brick 111 readily removed.

To prevent the rapidly travelling fuel from accumulating on the floor of each pass, I propose installing variously placed and inclined deflectors or "hurdles" 112 to direct the moving coal into 70 the gas stream above.

Firebrick baffle 71, Fig. 24, may be held in position by a water protected hollow member such as at 113 attached to the crown sheet 11.

Figs. 29 to 37 show a system of water-screen 75

protection of the sides and bottom of the ashpan and lower parts of the combustion chamber.

To supply these water screens at their lower ends I propose withdrawing water from the cooler 5 part of the boiler such as the bottom of the shell at 120 on Fig. 24, into pipe 121 having an emergency stop or control valve 122. This pipe 121 enters the forward end of the ash pan, as at 123, which should be supplied with suitable air tight 10 means of closure.

In these drawings there is a symmetrical right and left layout, though duplicate parts have often been omitted to avoid confusion of detail. To obtain the proper protection of the refractory 15 lining such as 124, the pipe screen should be in close contact with said lining.

Interior supply pipe 125 connecting with 123, is shown bent. Through the nozzles such as 126, it discharges into the inlets 127, of bottom header 20 128, to which are attached pipe risers 129 and 129A.

These risers enter a top header 130. Water leaves header 130 through bent pipe 131, passing 25 out through water leg thimble 132 and discharging 20 into outside header 133 to which 131 is detachably connected, as by a special hollow-headed nut 134.

Header 133 may supply the pipe 135, discharging 30 into the back head 13 of the boiler but controlled by a non-return valve 136. Another header 137 likewise feeds into a valve-controlled pipe 138, entering the boiler barrel at a point not shown.

These outside headers are free of the boiler 35 so as to allow for expansion adjustment. Likewise the pipes 131 have clearance within the thimble 132, the latter being closed by removable split plates 139 that stop the escape of furnace gases from or the entrance of cold air to the fire 40 box.

Bottom header 128, Figs. 33 to 36, has the inlet 127 in tight contact with the outlet nozzle 126 of pipe 125, as detailed in Fig. 36. To maintain 45 this contact, bolt 145 threads into a spider 146 protected by the water within pipe 125, only the bolt head 147 being exposed to the flame, said bolt head being hollow and filled with water from 50 125.

In Fig. 37 curved pipe 131 passes through split 55 plate 139 that bears against thimble 132. A boss or bearing piece 148 on this pipe is held against outside header 133 by the hollow headed nut 134 having a bearing flange 149. This nut is internally threaded and engages an outside thread on 60 the pipe 131. An external opening 150 in the opposite wall of 133 and closed by a plug or otherwise, provides access for turning the hollow nut.

Water screen tubes 129 are preferably of oval 65 rather than circular section, similar to 155 of Fig. 33 and are here shown as fitting into an oval opening in one of the headers 128. A preferred form of tube is of an oval section throughout most of its length but having a circular section at one or both ends as shown at 156, thus providing a more convenient means for upsetting the tube into the header.

If the oval form of entrance to the header is used, it may be necessary to twist the tube ends to allow enough metal between adjoining tubes. 70 This twist of the tube is shown at 157. The change from flat to circular section is shown in Figs. 34 and 36 at 58.

The term "oval section" is used in a general way and does not necessarily mean elliptical, it 75 all depending on the most convenient way of

rolling the tubing. As shown it has been assumed that circular tubes would be taken and flattened to the most convenient shape, the peripheral length being the same in both cases the ends shown as rounded. There is the possibility that tapered ends and slightly curved sides may be rolled more economically, all depending on the internal boiler pressure that must be resisted.

In Fig. 30 supply header 125L, similar to 125R shows an outlet 160 attached by an inside bolt 10 161 to a T shaped piece 162L at the bottom of the ash pan forming two openings 163L that may be used as an ash-discharge. Doors below, such as 164L Fig. 31 close these openings.

The other ends of this T are shown detachably connected to flat hollow plates 165 and 166 designed to protect the ash pan casing below and to likewise supply needed water to various risers. For instance, 165 connects to a flat, vertical riser 167 and protecting the front wall of 20 said ash pan from excessive heat, besides supplying the horizontal header 168L.

Also, hollow plate 166 supplies a rear vertical riser 170 that feeds into a rear header 171L.

Bolt 161 is similar in design to bolt 145. Also 25 the header 168R feeds into flattened tubes 169R, discharging into a top header and then out through a water leg thimble similar to 132.

Flattened pipe 172 is similar to 169, while 173 is a hollow, water filled protection piece. 30

Pipe riser 108 may connect flat plate 166 with the lower arch tubes 106, as shown in Figs. 29 and 32. It will be observed that this piping system is in two longitudinal, disconnected groups and that a leak in one group will not affect the 35 other. Should a leak occur in the right-hand system, valve 122R may be instantly closed preventing a draining of the boiler. The non-return valve 136R prevents the flow of the water and steam back to the fire box while repairs are 40 being made.

In Fig. 23 is shown an oil-burner 180, an oil supply pipe 181 and a valve controlled steam pipe 182 to operate it. This may be used to start the boiler, afterwards to be cut out when the coal 45 is ready to ignite and started up again during "stand-by" periods when the locomotive has stopped running, it not being always economical to keep the coal burners running even at a reduced speed. The amount of oil burned is only 50 that required to keep up the steam pressure and to maintain a heated combustion chamber, ready to ignite the coal whenever the latter is turned on.

In Fig. 24 it will be noted that hot gases and 55 ashes in suspension on leaving pass 72 are deflected into the bottom pass 73.

This pass shows a much larger cross section and the gas velocity is greatly reduced, thereby permitting some of the travelling ashes to fall 60 into the water screened ash pan below.

Referring back to the "second stage" air heater 46 of Fig. 21, wherein the air stream discharges both to the tender and to the rear top of the boiler it may be advantageous to carry air at two different temperatures to these points. For instance, the discharge to the tender at outlet 49, employed to force the coal into the burner 65, travels the longer and more exposed route and it might be the more economical to keep it at a lower temperature to prevent excess radiation, 70 while a higher degree of heat through passages 96 and 97, directly to the burner might greatly aid ignition at that point.

To accomplish this I have added features to 75 this heater which are shown diagrammatically

in Fig. 38. A partition 250 divides the heater casing into upper and lower portions. Incoming air from 30 is separated so that part may flow past damper 251 and below 250 and out at 49 to the tender or otherwise. The remaining air that passes above 250 is warmed by the greater surface of heating elements to a higher temperature and goes into 96 past the damper 99 and through 97 to the burner 65 (not shown). Another damper 252 opens or closes a rear passage 253 between the upper and lower portions of the heater casing.

By opening 252 a greater amount of air may pass through 49 and at a higher temperature. Also by closing damper 99 and opening 252 all the air goes through outlet 49, which may be necessary when required to move larger amounts of coal from the tender. Again, the closing of 251 would pass all the air to the top of the boiler, which at times might be desirable. Various open and partly open or closed dampers in combination will give such changes in the control of the boiler firing as may be desired.

Imperfect or unbalanced combustion in other parts of the fire box might call for additional amounts of air as for instance, in the last pass of the fire box. To supply such varying amounts it may be necessary to bleed off air from some source, as conduit 48, Figs. 23 and 24 into passages 254 controlled by a damper 255 and through a thimble 256 in the rear boiler leg 13, and beneath baffle 75 that may be used to diffuse the incoming air into the third pass 73.

While Fig. 21 shows a preferred type of second stage air heater that has a thermostat control of the hot gas discharge to the atmosphere, there is another system that may be used as an alternate, or in conjunction with this preferred type. This is shown in Fig. 39, a drawing essentially similar to that of Fig. 21.

The air of combustion from the fan or blower 28 while travelling toward heater 48 may be used to rotate a propeller device 260 within the conduit 29, that will in turn actuate a governor-like control 261. The propeller speed varies directly as the air velocity within 29, as does 261. This governor may be adjusted so that at a predetermined velocity, an electric contact may be established that causes current to pass through wires 262 and energize solenoid 263. This solenoid will rotate or otherwise operate damper 83, thus automatically controlling the hot gas escape out of 82 as required by the air supplied to the heater 46, this amount varying as the velocity of the air.

Several different rotative positions of 83 may be established, by having a corresponding number of different electrical contacts for different speeds of the governor. Also 261 may be used to supply steam that may directly operate damper 83.

Attention is drawn to the details of improvements as applied to the "first stage" heater 26 as installed on the forward part of the locomotive, Figs. 9 to 20. As before stated, the success of the steam heating of air will depend on proper designing, while its practicability will be questioned if maintenance is excessive, accessibility difficult, or reliability of operation at all in doubt.

The top of rear section 26B of this heater has been made parallel to the boiler barrel so as to contain curved steam tubes 275 assembled in pairs, as in Fig. 15 and detailed in Fig. 18, said tubes to be spaced closely, wasting the least amount of free space between them.

They should preferably extend from side to side of the enclosing casing and be symmetrical

about the boiler center line. Cast headers 276 are used to receive the ends of tubes 275, supplying the heating steam, and receiving the resulting condensation from them.

Vertical pipes 277 connect and support these headers, receiving steam from a supply header as 278 which may also be used as a drain for the condensate. Pipe 277 is fastened to the base piece of each header and enters freely the top of the header below, which bears on a shoulder 279 attached to pipe 277 and making a steam tight joint. A removal of the top of heater casing 280 allows each group of tubes 275 and attached headers 276 to be lifted out for repairs.

Each pair of tubes has been passed through numerous flat, thin plates 281 attached by soldering, brazing, etc., so as to transmit heat from the tubes to the plates and thus provide a maximum radiating or heating surface for the air to come in contact with. The size and spacing of the tubes and the dimensions of the plates will determine the efficiency of the installation as will the loss or increase of head due to frictional air resistance.

Each header 276 has a number of pairs of bent tubes as shown in Fig. 17, nine pairs to each header being here shown. Each header is supported on two connecting pipes 277. Six tiers of headers are assembled, one below the other. Fig. 10 shows a plan of seven groups of these tubes with headers 275 side by side and six layers deep.

Each header 276 shows a removable base piece 282 for cleaning and allowing access to the tubes 275 for calking, upsetting, etc. The loose fit as at flange 279 should allow for lateral expansion, while the weights of the headers or an adjustable clamp (not shown) should keep flange 279 steam tight on its seat.

Heating steam passes up the pipes 277, supplying headers 276 which feed into tubes 275, the condensate flowing back into 276 down 277 and into pipe 278 and outlet 283 to a later described conduit. Valve controlled air-vents (not shown) may be used to prevent air-bound conditions of the tubes 275.

The top of the forward section, 26A of the heater has been made to conform to the outlines of the cold air entrance of the "bell-mouth" 40, Figs. 3 and 4. Fig. 16 is a general cross section of 26A showing the groupings of the contained flat hollow plates or heating units, the scale being too small to show a sufficient number of plates to each group.

Fig. 20 is a top plan of a grouping of five plates that is self contained, ready to be detached and taken out through the removable top casing 286 of Fig. 16. It is a foreshortened plan view of the essentially similar three plate groups 287 of Fig. 16. Heating steam is supplied by the pipe 288, steam then enters the first plate unit 289 of any group from a circular riser 290 whose side is attached to the front edge or end of 289. A portion of the top edge of 289 is shown broken away to show its proposed construction.

Each plate unit is preferably made of thin, parallel sheets, suitably spaced as by occasional stitch riveting, the ends of the sheets bent over and lapped together as shown at 291. The rear part of 289 has a side opening opposite a like opening in the second unit, both being jointed and spaced by the connection 292 at the lower edge of 70 the side sheets, through which both steam and condensate may pass.

The front end of this second plate unit has likewise a side connection 293 like 292 and leads into the third unit which at its rear-end is like 75

wise connected to the fourth unit etc. The condensation is discharged from a fifth unit into a sump 294, thence to a drip pipe 295, that drains the other plate groups, finally discharging into outlet 296 of Fig. 9. Broken arrows show the flow of steam.

To provide proper steam circulation and the venting of any included air within these plates I attach across the tops of said plates a hollow member 297 having a small perforation entering each plate through which small amounts of steam may pass into 297, with access plugs 298 to clean perforations.

A detachable air venting piece 299 is shown connecting the removable plate unit groups, joining ends of 297, all feeding into one another and finally passing to the atmosphere through control valve 300.

Proper adjusting of the vents under 298 will cause the steam to flow to the top of the hollow heating plates instead of being confined to the bottom portions.

Riser 290 is to seat in a pocket in the pipe 288, that is made steam tight but allows the plate unit group to be lifted out for inspection. A like jointing to the drip pipe 295 is required.

In the part top plan, Fig. 10, the plate units are shown as 287 and the "fin-tube" groups as 275. In Fig. 9 condensation from 296 of the heater portion 26A and condensation from 283 of the heater portion 26B discharge into pipe 302, through a one way valve 303, to a discharge point such as 304 in the boiler feed supply line 305.

In Fig. 9, 305 is the inlet water supply pipe to a boiler feed pump 306 that cooperates with a feed-water heater 307 that may be heated by steam supplied through conduit 308, and delivering hot water through pipe 309 and boiler check valve 310 to the boiler.

Should but one feedwater heater unit be employed, the pre-heater condensate from the opposite or right side of the boiler can be delivered to the point 304 by the discharge of 283R and 296R into 311R and to a cross pipe 312 that passes through the boiler shell at the smoke box and empties into pipe 311L and to pipe 302 etc. Steam to operate the feed pump is supplied at 313.

Exhaust steam from the turbo-blower 28 may pass through pipe 315 to the interior pipe 278 that supplies the air-heater tubes, etc. A branch pipe 316 controlled by valve 317 may be used to deliver this steam to pipe 94 of Fig. 21 and thence to the jet in the secondary stack 4 (as has been described). Also heating steam from the main engine exhaust may enter pipe 318 controlled by valve 319, and pass into the air-heater as at 320, supplying conduit 288 of Figs. 16 and 20. Suitable by-pass connections (not shown) can be used to heat both sections of heater 16 from pipe 315 or from pipe 318 as may be desired. A valve may be placed in the line between 278 and the entrance to 316.

The hot air outlet 27 from 26B is flattened and becomes quite narrow where it passes through the running board 5, to a horizontal plane at 324 (Figs. 9, 10, and 13) where its cross section then alters to that of the joint at 325, where it connects with the inlet to the fan or blower 28.

This blower is hung or bracketed to the boiler shell 1 in a well known manner. Care in designing the discharge conduits and the "transition piece" 30, leading to the second stage heater 46, will smooth out the velocity-curve and cut down the friction head.

Speed control of the fans is preferably gov-

erned through a steam throttle (not shown), and the correlation of this with the various feeds, dampers, secondary stack regulation and main engine control, all tend toward the production of a perfected "thermal output".

Means for supporting the weight of the boiler on the new rear trailing truck are shown on Figs. 21 and 25, where a supporting bracket 330 attached to truck 9 with ball or roller bearings 331 receives said weight as through a shoe 332 shown attached to the mud ring 22 in any approved manner.

It has been long recognized that the existing boiler-draft system of discharging the main engine exhaust through a restricted nozzle and into the stack and causing excessive cylinder back pressure, was extremely uneconomical, but so far it has been the most reliable. As to the use of mechanical-draft systems, it was found that an induced draft such as might be developed by installing a fan in the smoke box to draw gases through the flues, was unsatisfactory, as the high abrasive action of the flying cinders rapidly destroyed the revolving blades of said fan.

Also, a forced draft fan required an air tight ash pan and fire box and when operated under the usual grate, either blew holes through the thinner parts of said bed, admitting unwanted "cold" air in too great quantities, or encountered too much resistance in passing through thicker parts of the bed and developing "dead" spots, requiring extra firing attention.

With the practical application of pulverized fuel, due to the ability of furnishing highly heated air to the locomotive boiler along with the successful installation of hot air fans or blowers operating the same, the grate is no longer needed, the finely divided coal being freely blown into the fire box and the resulting hot gases pass through the fire tubes and out of the stack, encountering a minimum of resistance. The power to overcome this resistance can be easily supplied, by the steam driven fans herein shown, thus removing this work from the main cylinders and employing them solely in moving the locomotive.

A large percentage of former wasted power is saved while the stack exhaust becomes continuous and comparatively noiseless, with a minimum of spark discharge. A simplifying of the main valve setting which at present is at best a compromise, becomes possible, resulting in still further steam economy.

Both types of fans, induced and forced draft, have recently been given road tests under service conditions and the locomotive tests have shown high percentages in fuel economy when compared with the alternate employment of a boiler draft as developed by the use of an exhaust steam jet in the smoke stack.

Besides the absence of an adequate sized fire box in which to burn the powdered coal while in substantial suspension and mingled with the hot air and travelling gases, the presence of the resulting ash in a finely divided state just before the entrance of the heated gases to the boiler tubes in quantities presented the problem of protecting said tubes from being clogged up. This is especially important when the tubes contain the super-heater elements which do not allow the passage of a tube cleaner.

My three-pass design for a fire box and low placed ash pan gives a longer travel for the fuel before it enters the fire flues, with more time to be consumed, while perforated and inclined baf-

flies in the last boiler pass, assisted by the described mushroom-shaped plugs before certain super-heater tubes, serve to at least partly protect them, and also to deposit ashes where they 5 may be removed.

By the substitution of a down draft for the usual upward draft, ashes only, instead of partly burned coal will remain in the draft stream when it reaches the ash pan, to which they will naturally gravitate. The ash-pan protection against excessive heat is largely made of slightly flattened pipe, being stronger against internal pressure than would flat surfaces of greater area, the latter requiring considerable stay-bolting.

15 The advantages of the crown sheet protector are obvious and give positive results as compared with various proposed low-water alarms that merely blow a whistle, leaving it to the engineer's attention to start up the boiler feed. Any 20 break down in a mere alarm is dangerous, as he has become dependent upon it and consequently neglect the usual precautions.

There is no heat loss in the second-stage air heater operations as the heat "bled" from the fire 25 box is later returned to it by the extra heated air. The temperature of escaping gas from the ordinary locomotive smoke stack is about 550 deg. Fahr. and it makes no difference whether this escape occurs at the main stack or through the 30 secondary stack 4, if limited to the same temperature. A thermostat control attends to that feature.

35 For the steam heating of incoming air, the first stage air heater has its heating units assembled with a view towards quick inspection, removal and repairs, as described. The innumerable thin "fin" plates, soldered to the pairs of curved tubes, truss each set against substantial deflection, and may be likewise occasionally trussed at right angles with an adjoining group 40 of tubes.

45 Excess heating steam to this heater may escape in sufficient quantities to insure the carrying away of included air within, that might otherwise cause said heater to become air bound. Considerable advantage is derived in the large amount of pure steam condensate that may be returned to a feedwater heater or to the boiler feed system, as 50 may be desired.

55 The "bell mouth" and shutter attached to the inlet of this air heater, as they do not extend beyond the locomotive outlines, only encounter the air resistance, that would otherwise be met further on, and is therefore negligible, while at the same time, the developed air pressure assists the fan in overcoming the interior resistances of the heater.

60 The location of the first heater on top of the boiler and at the front where it gets the freely flowing air, an interposed fan that is part induced and part forced, and naturally placed partly below the boiler curve, and the following low-placed second stage heater with its short-distance delivery to the fire box, all functioning 65 together, make a harmonious whole that it would be hard to improve on.

70 The removal of the cumbersome steam nozzle from the stack, along with some other draft devices, will give more room in the smoke box end and allow for a type of economizer placed between the feedwater heater delivery and a boiler check valve, giving a higher temperature of said feedwater if required. Though under boiler pressure and needing frequent inspection, the changes 75

in the front-end construction will permit greater access to the same.

On Fig. 9 are shown an indicated water pipe connection, 340 between said smoke box economizer and a 3-way valve 341. This valve is also connected with feed pipe 309 and with boiler check valve 310, and operates to pass the water received from 309 entirely to valve 310, or to the economizer or to both these points of delivery at the same moment and in varying amounts, as 10 may be required. The discharge from the economizer to the boiler is preferably through another check valve (not shown).

By a proper setting of valve 341, varying water 15 velocities through the economizer may be used and the resulting temperature of its discharge can be controlled.

In using exhaust steam in the first stage air pre-heater, a considerable percentage of otherwise lost heat may be returned to the boiler all 20 depending on the resulting temperature of the heated air.

Again, another advantage of a reheating in the second stage heater lies in the ability to produce 25 quite a range in the final air temperature at the coal burner, choosing that limit which will most speedily cause the combustible to flash into flame.

Satisfactory powdered coal burning being assured, a more continuous use of the locomotive 30 may be forecast. As compared with marine and stationary engine operations, locomotives are in use during a very small portion of the time, stopping after travelling a few hundred miles, but keeping up steam at the end of the run until it is time to return to the starting point, often a 35 "stand-by" of several hours, while the coal losses are considerable.

Such limited runs are largely due to the clogging of grates, the necessity of cleaning fires, etc. With the use of powdered fuel, the grates and 40 other adjuncts disappear and there seems to be no reason why the new type of locomotive cannot immediately proceed on its journey. It may be arranged at times to operate only one burner, while any prolonged wait would call for stopping 45 all coal burners and the starting up of a small oil burner to provide for the loss of radiated heat and any lowering of boiler pressure.

While new locomotives may be constructed to 50 embody these inventions, it will be observed that my drawings have been made with the idea of improving locomotives at present in active use. Mark's Mechanical Handbook, 1930 edition, lists the 2-8-4 type of locomotive shown on Sheet 1 of this patent application, as costing \$100,000. 55 Any substantial substitution of electric, gas electric or steam-turbine locomotives for the present steam locomotives in use would cause an almost complete capital loss on their present value, as there would be no other market for steam locomotives.

It is believed that my proposed improvements will prevent this, while providing economies far in excess of any that would be supplied by said substitutions, all these improvements costing but 60 a small percentage of the value of the existing locomotives.

I claim:

1. In a steam generator having a combustion chamber filled with hot gases and to which air 70 of combustion is supplied, means for preheating said air of combustion, said means comprising a steam-heated, first-stage preheater capable of delivering its contained air of combustion to a second-stage hot gas heated preheater, said hot 75

gas being directly withdrawn from said combustion chamber and delivered to heating means within said second-stage preheater at substantially the temperature of the combustion chamber, said heated air of combustion being discharged into said combustion chamber.

2. In a steam boiler having a combustion chamber supplied with air to promote combustion therein, a steam heated air preheater, a hot gas heated air preheater that uses quantities of hot gas obtained directly from said combustion chamber at substantially the temperature thereof, and an interposed fan or blower means for withdrawing air from said steam heated preheater and forcing said air through said gas heated preheater and into said combustion chamber.

3. In a locomotive boiler, a combination of an air conduit including a firebox and a smoke stack connected therewith and constituting a substantially closed system having an air intake at its front end and discharging products of combustion from the stack, a first-stage air preheater adjacent the entrance end of said conduit heated by exhaust steam and a second-stage air preheater receiving warm air from the first-stage preheater and heated directly by the hot gases from the firebox at substantially the temperature of the firebox and delivering highly heated air to the firebox.

4. A locomotive boiler construction comprising a firebox, a first-stage air preheater for heating the air by steam, a second-stage air preheater for directly heating the air by firebox gases connected thereto, said first-stage preheater being located principally above the horizontal central plane of said boiler and placed forwardly of said second-stage preheater, said second-stage preheater being located principally below said central plane, the higher placed preheater being arranged so as to supply its contained air of com-

bustion to the lower placed preheater and a fan located between the first and second stage preheaters for moving warm air through the first stage preheater and forcing the preheated air through the second stage preheater.

5. In a locomotive boiler having a combustion chamber with at least a first pass or ignition chamber to which the boiler fuel is supplied, an air of combustion preheater delivering air of combustion to said boiler, means for dividing said preheater into unequal heating parts so that one heating part heats its contained air of combustion to a higher temperature than that of the remainder, and means for delivering this more highly heated air of combustion to said first pass or ignition chamber, and means for delivering the remaining cooler air to another part of the ignition chamber.

6. A locomotive boiler having a firebox and a boiler, an air preheater having an entrance opening forwardly and heated by steam, a second preheater heated by the products of combustion from the firebox and delivering heated air into the firebox, a blower located between the entrance and the second preheater for forcing air to the second preheater, a controlled stack for discharging products of combustion which affect the second preheater, the remaining products of combustion serving to heat the boiler, and a main stack for discharging the latter products.

7. A locomotive boiler having a firebox, a first stage air preheater heated by steam, a second stage air preheater receiving air from the steam heated preheater and heated by part of the products of combustion at substantially firebox temperature and delivering the preheated air into the firebox, and means for accelerating the flow of air through the two preheaters, and means for discharging the products of combustion to the atmosphere.

EDMUND H. BLUNT.
